DESIGN FOR A GRAVE CANOPY

Lawrence F. Lang, Butler, Pa.

Application April 14, 1936, Serial No. 62,115

Term of patent 14 years

To all whom it may concern:

Be it known that I, Lawrence F. Lang, a citizen of the United States, residing at Butler, in the county of Butler and State of Pennsylvania, have invented a certain new, original, and ornamental Design for a Grave Canopy, of which the following is a specification, reference being had to the accompanying drawing, forming a part hereof.

Fig. 2 is a side elevation; and—

Fig. 3 is a perspective view.

I claim:

The ornamental design for a grave canopy as shown.

In testimony whereof, I have hereunto subscribed my name this 11th day of April, 1936.

LAWRENCE F. LANG.
